UNITED STATES PATENT OFFICE.

VERNON G. ERICKSON AND CLARENCE A. GOODAUDY, OF YUMA, COLORADO.

PAINTBRUSH.

Application filed January 8, 1926. Serial No. 80,086.

This invention relates to improvements in paint brushes, the general object of the invention being to provide means for preventing the paint or other material on the brush from running down the handle of the brush by forming a flange around the head of the brush which receives the material dripping or running over the head from the bristles.

10 Another object of the invention is to make the handle of the brush hollow to receive the paint caught by the flange and to provide a valve for preventing the paint from running out of the handle when the brush is 15 reversed or placed in horizontal position.

A further object of the invention is to make the bristle carrying part removable from the handle part, so that new bristles can be used with the old handle when the 20 old bristles have become worn.

This invention also consists in certain other features of construction and in the combination and arrangement of the several parts, to be hereinafter fully described, 25 illustrated in the accompanying drawings and specifically pointed out in the appended claim.

In describing our invention in detail, reference will be had to the accompanying 30 drawings wherein like characters denote like or corresponding parts throughout the several views, and in which:—

Figure 1 is a sectional view of the improved brush.

35 Figure 2 is an edge view thereof.

As shown in these views, the bristles 1 forming a unit in which a channel is provided with a groove 3 which passes around the member. The stock 4 is formed of metal 40 and is adapted to receive the part 2, and said stock has a rib 5 formed thereon which will engage the groove 3, when the part 2 is forced into the stock to frictionally hold the part 2 in place. Thus when the bristles 45 have become worn, the part 2 can be pulled from the stock and thrown away and a new bristle carrying part substituted. A flange 6 is formed around the member 4 and is spaced from its end so as to form a chamber 7 which surrounds the bristle carrying part and will catch any paint or other material running off the brush when the same 50 is being used in overhead work. This mate-

rial will pass from the chamber 7 into the stock 4 through the perforations 8 and the material in the stock will pass through the valve seat 9 and enter the hollow handle 10. A valve 11, held in place by a cage 12, acts to close the opening in the valve seat when the brush is reversed so as to prevent the paint in the hollow handle from flowing back into the stock 4 and through the openings 8. The handle 10 threadedly engages the stem of the stock 4 so that it can be detached and emptied when full of paint.

From the foregoing, it will be seen that we have provided a paint brush, the handle part of which is formed of metal so that it will last indefinitely and which detachably holds the bristle carrying part in place, so that new bristles can be substituted for the old ones when desired or necessary.

The brush also prevents the painting material from running down the handle on to the hands of the user and from dripping on floors and the like when the brush is being used in overhead work. The paint is caught and held in the handle and the handle can be emptied whenever desired by detaching it from the stock.

It is thought from the foregoing description that the advantages and novel features of our invention will be readily apparent.

We desire it to be understood that we may make changes in the construction and in the combination and arrangement of the several parts, provided that such changes fall within the scope of the appended claim.

What we claim is:—

A brush of the class described, comprising a hollow stock having a flange at its open end forming a chamber, a bristle carrying member detachably held in the open end of the stock, said stock having perforations therein placing its interior in communication with the chamber, a hollow handle connected with the stock and a valve for preventing the paint material from passing from the hollow handle from the stock when the brush is reversed.

In testimony whereof we affix our signatures.

VERNON G. ERICKSON.
CLARENCE A. GOODAUDY.
